AIR CONDITIONING APPARATUS

Walter L. Fleisher, New York, N. Y.

Application August 15, 1936, Serial No. 96,199

8 Claims. (Cl. 183—45)

This invention relates to air conditioning apparatus and is a continuation-in-part of applicant's copending application Serial No. 8,603, filed February 28, 1935, now matured into Patent No.

5 2,054,809, issued September 22, 1936, and Serial No. 65,315, filed February 24, 1936.

The inventions disclosed in said copending applications utilize bundles of straight, substantially parallel filaments or fibres of non-absorbent, 10 non-hygroscopic, non-corrodible, smooth-surfaced material, preferably oriented capillary glass threads. Each filament is relatively long compared to its thickness, the diameter of the filaments being so small that the bundle forms a

15 great number of very fine, smooth, frictionless passages between the fibres, of substantially uniform cross-section. The surfaces of the filaments are neither water repellent nor absorptive, or water occluding. They are easily wetted and 20 water is readily conducted therealong. The vast surface provided by the filaments insures intimate contact between water flowing therealong and air drawn therebetween under the influence of a fan or the like. The air picks up water vapor and 25 approaches saturation at its initial wet bulb temperature, so that the dry bulb temperature of air leaving the apparatus is substantially below the entering dry bulb.

The filaments are exceedingly fine and occupy 30 but a small percentage of the total cross-sectional area of a container or the like in which they are positioned. Thus, in a container having a cross-sectional area of 400 square inches, the total 35 cross-sectional area of the threads may be approximately 3 square inches. The threads, therefore, are spaced from each other, the space between the threads constituting passage space for air and water. It is of the utmost importance 40 that the threads be maintained in spaced relation, to prevent undue restriction of the air and water passages and to prevent bypassing of air around the filaments, regardless of the position, whether horizontal or vertical, in which the threads are 45 utilized and regardless of jarring, in handling or in transit, of assembled units in which the threads are placed.

While it is desirable to have at least a majority 50 of the capillary threads running substantially vertically (assuming a vertical air flow) and parallel to each other, it is desirable to have some of the capillary threads inclined at an angle to the vertical. These inclined threads are distributed throughout the container. The contact 55 between the inclined threads and the vertical

threads gives rise to a frictional resistance which tends to hold the vertical filaments in desired spaced relation. The vertical threads are more efficient than the inclined threads in effecting the humidification of air; and the desirability of 5 maintaining a high humidification efficiency mitigates against the use of a sufficient number of inclined threads securely to hold the vertical threads in position when they are unduly shaken or jarred in handling or transit. Hence, additional means for securing the threads in position must be provided in order to insure the safe 10 transit of assembled capillary thread units or cells.

The object of the present invention is to provide a method of and means for retaining capillary threads in substantially fixed position within a suitable container or casing, to prevent shifting and packing of the capillary threads when the container is jarred in handling or in transit or 20 when the container is so positioned that the normally vertical capillary threads are horizontal or inclined at an angle to the vertical, thus to maintain the threads in proper spaced relation.

A feature of the invention resides in securing 25 capillary threads in substantially fixed position in a confining basket, or the like, by providing lacing means extending through and between the capillary threads.

Another feature of the invention resides in 30 securing substantially parallel capillary threads in substantially fixed position in a confining basket, by providing a plurality of other capillary threads inclined with respect to and in frictional engagement with said first-mentioned capillary threads. 35

Another feature of the invention resides in 40 positioning oriented capillary threads of glass or the like within a confining container and securing the threads in substantially fixed position by lacing means secured to the container, at least a portion of said lacing means extending between the filaments at an angle to the axes of said 45 filaments.

Another feature of the invention resides in 45 positioning oriented capillary threads of glass or the like within a confining container, and securing the threads in substantially fixed position by means of lacing extending between the capillary threads, the lacing being arranged symmetrically to prevent the threads from shifting, regardless of 50 changes in the position of the container.

Another feature of the invention resides in 55 securing capillary threads in substantially fixed position in a confining container or the like by providing lacing means extending between the

threads, said lacing means being arranged to give maximum support to the threads proximate the center of the container.

Other objects, features and advantages of the invention will be more apparent from the following description to be read in connection with the accompanying drawing, in which:

Fig. 1 is a perspective view, partly broken away, of a capillary cell or basket in connection with which the invention is adapted to be employed;

Fig. 2 diagrammatically illustrates one type of lacing arrangement adapted to carry out the invention; and

Fig. 3 is a vertical section through the cell of Fig. 1.

Referring now to the drawing and more particularly to Fig. 1, 20 designates a basket or casing having openings at its upper and lower extremities to provide for the passage through the basket of air and liquid. A coarse net 21, of wire or the like, covers the opening at the upper extremity of casing 20 and a coarse net 22, of wire or the like, covers the opening at the lower extremity of casing 20. Supported by the screen 21 is a layer 23 of horizontally disposed capillary threads, and supported by screen 22 is a layer 24 of horizontally disposed capillary threads. Between horizontal layer 24 and screen 21 are positioned vertical capillary threads 25. The layer 23 served to remove large particles of foreign matter, such as cotton lint or the like, from air entering the basket, thus to prevent clogging of the passages between threads 25. Layer 24 serves to collect water from the ends of the vertical threads 25 and to cause the agglomeration of such water into drops of such size and weight that they are not entrained by air passing from the container, so that no eliminators are required in connection with the apparatus.

A preferred lacing arrangement for preventing the threads 25 from shifting and packing, is diagrammatically illustrated in Fig. 2. A lacing 26, of stout cord or any other material which is flexible and strong, is firmly secured to screen 21 at any desired point, such as, for example, the point 1 in the forward right hand portion of screen 21. By means of a long firm needle of any desired type, lacing cord 26 is run diagonally through the vertical strands 25 (not shown) to point 2, at the center of screen 22. The cord 26 is looped around the screen 22 at point 2 and is then run diagonally through the threads 25 to point 3 in the rearward right hand portion of screen 21. Cord 26 is looped about the screen 21 and then run vertically downwardly to point 4 in the rearward right hand portion of screen 22. In substantially the same manner, the lacing cord 26 is successively routed through points 5-13 inclusive, the last point, 13, coinciding with the starting point 1, at which the cord 26 is firmly secured.

In a preferred form of the invention, the lacing is done by means of a single continuous cord, immovably secured only at its extremities. This arrangement is preferred because it permits equalization of load between the various passes of the lacing. If desired, however, a plurality of separate and/or separately fastened lacing sections may be used instead.

The arrangement illustrated in Fig. 2 provides symmetrical bracing and retaining means proximate the central portion of the cell, the lacing 26 defining the outline of an octahedron. Thus, no matter which way the basket is turned, the threads 25 will be equally well supported. Moreover, the greatest support will be applied to the

center of the mass of vertical threads 25, where it is most needed.

If the lacing 26 is very tightly strung between the screen 21 and the screen 22, shifting of the threads 25 will be minimized, but even when lacing 26 is not very tightly strung, but has some slack, the threads 25 will be prevented from shifting sufficiently to impair operation of any air conditioning apparatus in which the basket is employed. Moreover, the threads 25 will not be drawn together by the lacing 26, but will be maintained in proper spaced relation.

While the geometrical figure formed by the lacing 26 in the center of the basket preferably takes the form of two opposed four-sided pyramids having coinciding bases, it will be apparent that the lacing may be arranged to form symmetrical figures having different shapes, without departing from the scope of the invention. If desired, of course, a non-symmetrical lacing arrangement may be employed.

Fig. 3 illustrates the manner in which the diagonal strands 25a are positioned within the casing 20, these strands being intermixed with and in frictional contact with the vertical strands 25. As explained in applicant's above-identified co-pending applications, the parallelism of strands 25 is of considerable importance in providing the proper conditioning of air passing through the cell. By positioning strands 25a more or less parallel to each other, these air-conditioning benefits of parallel thread arrangement may, to a substantial degree, be retained; thus, the inclined strands serve not only to help secure the vertical strands in position, by frictional contact therewith, but also, assist in the conditioning of air passing through the cell.

The air films travelling vertically through the cell are broken up at those points where the vertical and inclined strands touch each other, but this action is not undesirable, since it creates turbulence which helps to clean the air. It is to be understood, of course, that a considerable portion of the strands, preferably at least half of them, should be vertical, to provide efficient humidification of the air.

Although the invention is preferably practiced as above described, it is to be understood that the foregoing description and accompanying drawing are illustrative only, and that many variations thereof may be made within the purview of the invention; and any arrangement in which oriented capillary threads are prevented from shifting and packing by means of lacing, other capillary threads, or the like, extending through and/or between the threads, parallel to and/or at an angle thereto, is deemed within the purview of the invention.

I claim:

1. In an apparatus of the character described, a casing containing a plurality of oriented capillary threads, retaining means at opposite ends of said threads, and bracing means extending between said threads and secured to said retaining means, to prevent shifting of said threads with respect to the sides of said casing, said bracing means being arranged in the outline of a symmetrical geometric figure proximate the center of said casing.

2. In an apparatus of the character described, a plurality of oriented capillary threads, retaining means at opposite ends of said threads, and lacing means extending between said threads and connecting said retaining means in a plurality of passes, at least some of the passes being non-

parallel to the axes of said threads, said passes comprising different sections of a continuous lacing means.

3. In an apparatus of the character described, a plurality of oriented capillary threads and lacing means extending between said threads in a plurality of passes for preventing packing and shifting of said threads, certain of said passes being slopingly arranged to form the outline of an octahedron.

4. In an apparatus of the character described, a plurality of oriented capillary threads and lacing means extending between said threads in a plurality of passes for preventing packing and shifting of said threads, certain of said passes being substantially vertical and other of said passes being slopingly arranged to form the outline of an octahedron.

5. In an apparatus of the character described, a plurality of oriented capillary threads, retaining means at opposite ends of said threads, and means for preventing transverse shifting and packing of said capillary threads, said last-mentioned means including lacing means extending between said threads and connecting said retaining means in a plurality of passes, at least some of the passes being non-parallel to the axes of said threads, at least some of said passes comprising different sections of a continuous lacing means.

6. In an apparatus of the character described, a casing having a pair of openings at opposite sides thereof, a plurality of oriented capillary threads disposed within said casing, said threads being arranged in a direction substantially parallel to the direction between said openings, retaining means fixedly arranged at opposite ends of said threads, and lacing means extending be-

tween said threads and connecting said retaining means in a plurality of passes, at least some of the passes being non-parallel to the axes of said threads, at least some of said passes comprising different sections of a continuous lacing means.

7. In an apparatus of the character described, a casing having a pair of openings at opposite sides thereof, a plurality of oriented capillary threads disposed within said casing, said threads being arranged in a direction substantially parallel to the direction between said openings, retaining means fixedly arranged at opposite ends of said threads, and lacing means connecting said retaining means in a plurality of passes extending between said threads and substantially throughout the interior of said casing, at least some of the passes being non-parallel to the axes of said threads, said passes comprising different sections of a continuous lacing means.

8. In an apparatus of the character described, a casing having a pair of openings at opposite sides thereof, a plurality of oriented capillary threads disposed within said casing, said threads being arranged in a direction substantially parallel to the direction between said openings, retaining means fixedly arranged at opposite ends of said threads, and lacing means connecting said retaining means in a plurality of passes extending between said threads and substantially throughout the interior of said casing, at least some of the passes being non-parallel to the axes of said threads, said passes comprising different sections of a continuous lacing means, the ends of said continuous lacing means being firmly secured to said retaining means, the remaining portions of said continuous lacing means being slidably associated with said retaining means.
